UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

ACTUATING MECHANISM FOR WASHING-MACHINES.

1,241,896.

Specification of Letters Patent.

Patented Oct. 2, 1917.

Application filed February 14, 1916. Serial No. 78,140.

To all whom it may concern:

Be it known that I, ALPHEUS W. ALTORFER, a citizen of the United States, a resident of Peoria, in the county of Peoria and State of Illinois, have invented new and useful Improvements in Actuating Mechanism for Washing-Machines, of which the following is a specification.

This invention has reference to washing machines and relates particularly to that type of machine, the washing element or elements of which comprise a vertically movable member, which during the raising and lowering of the same, is rotated first in one direction and then in the opposite direction.

One of the objects of the present invention is to construct the washing element in the form of a pounder, the same being provided with a valve so that after the pounder has been lowered and when it is being elevated, a vacuum is created to lift the clothes, the operating means for said pounder during the lowering and raising of the same, rotating it first in one direction and then in the opposite direction.

The invention has for a further object, to provide in a washing machine, a reciprocating rotary washing element and means for operating the same to reciprocate it, and during such reciprocation, to rotate it first in one direction and then in the opposite direction; said operating means including an operating lever and connections between said lever and washing element for reciprocating the same, and other connections between said lever and said washing element for imparting intermittent rotary movement in opposite directions thereto, during the reciprocation thereof.

The invention has for a further object to provide in a washing machine, a reciprocating rotary washing element, and means for operating the same, said means including connections with the washing element which will simultaneously reciprocate and intermittently rotate the same in opposite directions; and gearing connected with said operating means, said gearing adapted to

operate a balance or fly wheel, which will 50 rotate continuously during the operation of the operating means, said gearing, balance or fly wheel, operating means and washing element being mounted upon the hinged cover or lid of the machine.

That the invention may be more readily understood, reference is had to the accompanying drawings forming part of the present invention, in which:—

Figure 1 is a sectional view of a part of 60 the hinged lid or cover for a washing machine, showing my improvements supported thereon, parts being broken away and other parts being shown in dotted lines; in the position shown, the washing element is in 65 an elevated position;

Fig. 2 is a view of the washing element and operating means therefor, somewhat similar to Fig. 1, with the exception that parts have been omitted and the washing 70 element is shown in cross section and in its lowermost position;

Fig. 3 is a view similar to Fig. 2, with the exception that the washing element is omitted and the operating means is in the 75 position intermediate the position of the parts shown in Figs. 1 and 2;

Fig. 4 is a cross section in plan, of the parts as they are shown in Fig. 3, and with the balance or fly wheel connected;

Fig. 5 is a vertical sectional detail of the shaft on which the washing element is carried and the driving connections between the operating means and said shaft;

Fig. 6 is a perspective view of a casting in 85 which the shaft supporting the washing element, is carried, said casting serving as a guide during the raising and lowering of the shaft and upon which is slidably mounted the head shown in Fig. 7, and

Fig. 7 is a perspective view of a head adapted to be slidably mounted on the casting shown in Fig. 6 and to which is connected the lever for operating the shaft carrying the washing element, and between 95 which and said shaft suitable connections are made for oscillating the shaft during the sliding movement of said head.

Like characters of reference denote corresponding parts throughout the figures.

In the drawings, no attempt is made to illustrate the construction of the washing machine proper, as this construction is well known and understood by those skilled in the art. For purposes of illustration, only a portion of the hinge lid or cover of the machine is shown which supports the operating parts of the machine, and when the lid or cover is lowered, the washing element is in operative position, and when the lid or cover is raised, the same is in inoperative position; that is, with respect to the interior 15 of the washing machine.

1 designates the lid or cover of the machine in which is provided the centrally disposed opening 2 through which is carried, the operating shaft 3. On the lid or 20 cover 1 of the machine are adapted to be secured the sections 4 and 5 of a casing in which are contained the movable parts of the operating mechanism which are employed for actuating the shaft 3, said sections being adapted to be bolted or otherwise 25 suitably secured together, and said sections being preferably of the formation shown in Figs. 1, 2, 3 and 4. The section 4 has a bearing 6 disposed within the opening 2 of 30 the lid or cover 1 and in said bearing is journaled the shaft 3 which is adapted to move therethrough, and said shaft is also journaled in a bearing 7 in the upper portion of said section 4 and to have movement 35 therethrough.

On the lower end of the shaft 3 is secured a washing element 8, preferably of the pounder type; that is, said element is semi-spherical in shape, see Fig. 2, and is formed 40 with the boss 9 for securing the same to the lower end of the shaft 3. The wall of said element 8 is provided with openings 10, covered by cone shaped members 11, for purposes which will be explained. Said element is further provided in its upper portion with openings 12 and extending transversely of the element 8 and located between the openings 10 and 12 is a partition 13, having the opening 14, said opening being 50 normally closed by a valve plate 15 loosely resting on the partition 13. In operation, when the shaft 3 is lowered, the element 8 will pass through the water and depress the clothes, the water and some air will pass 55 through the openings 10, but a large portion of the air will be forced up through the opening 14 in the partition 13, raising the valve 15, and the air will be allowed to escape through the opening 12. When the 60 shaft 3 is raised, the valve 15 will close the opening 14 and create a vacuum, tending to lift the clothes with said washing element. The purpose of the cone shaped members on the element 8 is to provide projections which

will not only agitate the water as the element 65 is oscillated with the shaft 3, but will also move the clothes in the water.

Carried on the shaft 3, is the hub or bearing 16 of a casting 17. The body portion of this casting is of considerable length, extending cross-wise of the hub or bearing 16, as shown in Fig. 6, and provided with bearing portions 18 at its opposite ends adapted to engage and slide upon correspondingly, shaped surfaces in the section 4 to guide the 75 casting 17 in its movement down and up, in said section 4. The shaft 3 rotates in the bearing portion 16 of said casting 17 and as a preferred way of carrying said casting on said shaft, cotter or other suitable pins 16^a 80 are passed through the shaft 3 above and below the bearing 16 to hold it in position during the rotation of the shaft, and to permit the casting to be raised and lowered with said shaft. Slidably carried to move 85 forward and back on said casting 17 and across the shaft 3 to which said casting is secured, is a head 18', see Fig. 7, said head being formed with the slotted way 19 to receive the body of the casting 17 on which it 90 slides. The hub or bearing 20 carries a stub shaft 21 of a gear wheel 22, and encircling said hub or bearing 20, is a sleeve 23 formed on one end of an arm or bar 24, and depending from and secured to said head 18', is a 95 yoke 25 having a vertically disposed opening 26 in which is carried a vertical portion 27 of a rod, the horizontal portion 28 of which passes through and has movement in an opening 29 extending transversely through 100 the shaft 3. The gear wheel 22 is carried on a shaft 30 which is journaled in an elongated bearing 31 extending laterally from the section 5 of the casing, and meshing with said gear wheel is a pinion 32 carried on 105 the inner end of a shaft 33 which is journaled in an elongated bearing 34 extending laterally from the section 5 of the casing, see Fig. 4, and on the outer end of said shaft 33 is carried a balance or fly wheel 35. In 110 Fig. 4 the shaft 33 is shown having a roller bearing 36, the purposes of which are well understood.

When the parts which have been previously described, are assembled in the manner shown in Fig. 4, the sections 4 and 5 of the casing will retain the same in an operative position as shown, and to remove any of the parts or to gain access to the same, all that is necessary is to remove the section 5 115 of the casing, which will detach the gearing from the arm or bar 24 and allow the same to be removed, if desired.

The arm or bar 24 passes out of the casing through a vertically disposed slot 36, in 120 the section 5, see Fig. 4, and said arm or bar 24 is pivotally connected at 37 with the casting 38 and said casting 38 has a pivotal

connection at 39 with the bracket 40 secured to the lid or cover 1 of the machine. Said casting 38 is formed with sockets 41 and 42 in which may be inserted an operator's handle or rod 43 to oscillate said casting 38 on its pivot, for the purpose of reciprocating the bar or rod 24. If the operator wishes to actuate the mechanism while standing, it is preferable to place the operator's rod or handle in the socket 41 of the casting 38, but if it is desired to actuate the mechanism in a seated position, it is preferable to put the operator's rod or handle in the socket 42.

In the operation of the mechanism contained within the sections 4 and 5 of the casing, when the arm or bar 24 is reciprocated, the head 18' is moved forward and back on the casting 17 and during such movement, because of the connection between said head 18' with the short shaft 21 and the gear wheel 22, the gear wheel will be rotated and as it is rotated, the casting 17 will be raised and lowered, and because of the connection between the casting 17 and the shaft 3, said shaft will be raised and lowered for the purpose of elevating and lowering the washing element 8 in the washing machine. Through the connection of the rod 28 between the yoke 25 of the head 18' and the shaft 3, as the head is moved forward and back on the casting 17 and across the shaft 3 said rod will be reciprocated through the shaft, and at the same time, oscillate it first in one direction and then in the opposite direction, such movement occurring simultaneously, as will be understood, with the raising and lowering of the shaft 3 and the washing element 8. The rotation of the gear wheel 22 will impart movement to the shaft 33 through the pinion 32 and continuously rotate the balance wheel 35, for purposes which will be understood.

What I claim is:

1. In a machine of the character described, in combination, a washing element, a shaft to operate said element, a casting carried on said shaft, a rotatable member, a head slideable on said casting, means connected to said rotatable member and said head to rotate said member and simultaneously reciprocate said head on said casting, the rotation of said member raising and lowering said casting and said shaft, and connections between said shaft and said head adapted to oscillate said shaft during the reciprocation of said head.

2. In a machine of the character described, in combination, a casing, a washing element, a shaft to operate said element, said shaft being reciprocally and rotatably journaled in said casing, a casting carried on said shaft and having bearing members adapted to move on the walls of said casing to guide said casting as the same is recipro-

cated with said shaft, a rotatable member, 65 a head slideable on said casting, means connected to said rotatable member and said head to rotate said member and simultaneously reciprocate said head on said casting, the rotation of said member raising and lowering said casting and said shaft, and connections between said shaft and said head adapted to oscillate said shaft during the reciprocation of said head.

3. In a machine of the character described, in combination, a washing element, a shaft to operate said element, a casting carried by said shaft, a rotatable member, a balance wheel operated by said member, a head slideable on said casting, means connected to said rotatable member and said head to rotate said member and simultaneously reciprocate said head on said casting, the rotation of said member raising and lowering said casting and said shaft, and connections between said shaft and said head adapted to oscillate said shaft during the reciprocation of said head.

4. In a machine of the character described, in combination, a washing element, 90 a shaft to operate said element, a casting carried on said shaft, said shaft being rotatable in said casting and said shaft and casting adapted to be moved together in the direction of the length of said shaft, a rotatable member, a head slideable on said casting, a lever, operating connections between said lever and said rotatable member and between said lever and said head, whereby when said lever is operated said head will 100 slide on said casting while at the same time said rotatable member is revolved, and connections between said head and said shaft to oscillate the shaft during the sliding movement of said head.

5. In a machine of the character described, in combination, a washing element, a shaft to operate said element, a casting on said shaft, a rotatable member, a head slideable on said casting, a lever, an operating bar connected to said lever and connections between said bar and said head and between said bar and said rotatable member, the rotation of said member raising and lowering said casting and said shaft, and a rod connected to said head and having a 110 slideable connection with said shaft, said rod adapted to oscillate said shaft during the reciprocation of said head.

6. In a machine of the character described, in combination, a washing element, a shaft to operate said element, a casting having a bearing to receive said shaft, means to hold the casting on said shaft to allow the shaft to rotate in the bearing of said casting and for insuring the shaft reciprocating with said casting, a head having a slotted-way to receive said casting and to

permit said head to slide on said casting, means for reciprocating said head on said casting and to raise and lower said shaft, and means operated by said head to oscillate 5 said shaft.

7. In a machine of the character described, in combination, a washing element, a shaft to rotate said element, a casting carried on said shaft, a head slidable on said

casting, said head having a bearing, a gear 10 wheel having a shaft journaled in the bearing on said head, a balance wheel geared to said gear wheel, a bar having a sleeve journaled on the bearing of said head, a lever for operating said bar, a rod having a 15 pivoted connection with said head and a slidable connection with said shaft.

ALPHEUS W. ALTORFER.
